(57) **CLAIM**

The ornamental design for a healthcare robot, as shown and described.

DESCRIPTION

FIG. 1 is a sectional view of a healthcare robot showing our new design;

FIG. 2 is a front view thereof;

FIG. 3 is a side view thereof; and,

FIG. 4 is an isometric view thereof.

This design is aimed at improving the quality of life for the elderly which is a key focus area of the healthcare robot.
